UNITED STATES PATENT OFFICE.

DAVID BASCH, OF NEW YORK, N. Y.

COLLAR-SUPPORT.

1,133,457.

Specification of Letters Patent. Patented Mar. 30, 1915.

Application filed December 19, 1911. Serial No. 666,784.

To all whom it may concern:

Be it known that I, DAVID BASCH, a citizen of the United States of America, and a resident of the city, county, and State of 5 New York, have invented certain new and useful Improvements in Collar-Supports, of which the following is a specification, reference being had to the accompanying drawing, forming a part thereof.

10 My invention relates particularly to that class of resilient supports which are adapted to be attached on the inside of a garment or collar to hold the same in an upright position, and which are readily removable for 15 allowing the garment or collar to be laundered, and has for its object the providing of a support of novel construction which possesses the foregoing and certain other advantages which will be fully set forth in 20 the specification and the novel features of which I will set forth in appended claim.

In the drawings, Figure 1 is a front elevation of a resilient supporting member, showing circular rings formed at each end 25 thereof. Fig. 2 is a front elevation of a part of the resilient supporting member, showing a web attached thereto in a novel manner. Fig. 3 is a view similar to Fig. 2, but shows a slightly different form of web. Fig. 30 4 is a sectional view more or less diagrammatic taken on the line 4—4 Fig. 2. Fig. 5 is a sectional view more or less diagrammatic taken on line 5—5 Fig. 3. Fig. 6 is an enlarged sectional view of the device shown 35 in Fig. 3 showing a section of the wire of which the supporting member is made, with a cover of thread wound about it.

Referring more specifically to the drawings, in which like characters of reference 40 designate like parts in all of the figures, 10 designates a resilient supporting member comprising a wire 11 of spring metal and a fibrous covering 12. This covering may be of any suitable material such as silk, linen 45 or cotton thread. The wire is bent to form regular alternating waves and rings 13 at each of its ends, the whole being in the same plane. Webs of textile fabric 14 and 14^A are secured to the rings 13 by means of eyelets 15, the shanks of which pass through the rings, and the flanges of which are pressed down upon the outer surfaces of the fabric immediately over the rings. The textile fabric 14 and 14^A may be of any suitable 50 material and color, and may be fashioned

into a web in a number of different ways, without departing from the spirit of my invention. In Fig. 4 I have shown the web as fashioned from a single length of cloth folded in to three layers, and in Fig. 5 a 60 single length of cloth folded into four layers with a row of stitching at its edges. Obviously the number of layers of the fabric is immaterial although I prefer to use at least two layers so as to cover both sides of 65 the metallic supporting member. As will be seen from the drawing the outside diameter of the flange of the eyelet is approximately equal to the inside diameter of the ring 13. The flanges of the rivet are of such 70 a width as to firmly engage the ring, when the whole is assembled, so that it effectively prevents the fibrous covering of the ring becoming unraveled or unwound. This is a great advantage, as it prevents the wire 75 from becoming rusted and staining the collar, thus overcoming a fault now prevailing in similar devices. Also the fabric web is held rigidly in place so that an attached collar can not fall down. The cloth web projects 80 on all sides from the eyelet so that it may be stitched onto the collar. It is an important feature of this invention that the cloth web projects beyond the ends of the metallic supporting member so that it forms 85 a cushion for the wearer and prevents the ends of the wire member chafing the neck.

In using my novel form of collar support, the devices are placed inside the collar in 90 substantially upright positions at desired intervals, and the collar sewed to the webs at its top and bottom and sides, or through the eyelets. I thus provide a resilient collar support which cannot be displaced, of which the webs are fastened thereto much more 95 securely than if merely sewed in as has heretofore been the practice and arranged to prevent the wire member from coming in contact with the neck of the wearer, and in which no rusting of the wire member is possible to stain the attached collar. 100

What I claim as new and desire to secure by Letters Patent is:

A device of the character described, comprising a supporting member of resilient 105 wire bent to form alternate waves to provide longitudinal elasticity to said member, and to form a ring at each end in the same plane with the wave portion thereof, a thread wound about said wire, webs of textile fab- 110

ric folded over the rings and rigidly secured thereto in position to cover only the ring portions of said member, means for securing said webs to said rings, said means comprising double-flanged metallic eyelets, the outside diameter of said eyelet flanges being about equal to the inside diameter of

said rings, the webs of fabric being arranged to project beyond the wire supporting member to form cushioning edges.

DAVID BASCH.
